UNITED STATES PATENT OFFICE.

ALFRED C. ABRAMSON, OF ROCKFORD, ILLINOIS.

DESIGN FOR A SEWING-MACHINE CABINET.

SPECIFICATION forming part of Design No. 35,221, dated October 22, 1901.

Application filed September 24, 1901. Serial No. 76,403. Term of patent 7 years.

To all whom it may concern:

Be it known that I, ALFRED C. ABRAMSON, a citizen of the United States of America, residing at Rockford, in the county of Winnebago and State of Illinois, have invented and produced a new and original Design for Sewing-Machine Cabinets; and I do hereby declare the following to be a full, clear, and exact description of the same, reference being had to the accompanying drawing, forming a part thereof.

The accompanying drawing is a perspective view of my new design for sewing-machine cabinets.

The design consists in a cabinet substantially of the configuration shown.

The cabinet comprises the single-paneled

ends A, the single-paneled front B, ornamented with the carving C, the bas-relief columns D, flanking the front B, the ogee lintel E, supported by the columns D, the top F, and the railing G.

Having described my invention, what I claim as new, and desire to secure by Letters Patent, is—

The design for a sewing-machine cabinet herein shown and described.

In testimony whereof I have signed my name to this specification in the presence of two subscribing witnesses.

ALFRED C. ABRAMSON.
